(57) **CLAIM**

I claim the ornamental design for an inspection light, as shown and described.

DESCRIPTION

FIG. 1 is a front perspective view of an inspection light in accordance with the present invention

FIG. 2 is a left side view of the inspection light of FIG. 1.

FIG. 3 is a right side view of the inspection light of FIG. 1.

FIG. 4 is a front view of the inspection light of FIG. 1.

FIG. 5 is a rear view of the inspection light of FIG. 1.

FIG. 6 is a top view of the inspection light of FIG. 1; and,

FIG. 7 is a bottom view of the inspection light of FIG. 1.

The broken line showing represents portions of the article not claimed and forms no part of the claimed design.
